FIG. 2

FIG. 1

FIG. 1 is a front perspective view of a side delivery rake showing my new design.

FIG. 2 is a perspective view thereof, with the tine members partially shown for ease of illustration; the broken line representation in FIG. 2 is intended to represent the tine members which are understood to continue uniformly throughout the rake wheel area.

We claim:

The ornamental design for a side delivery rake, substantially as shown and described.
